SHOE

Perley G. Flint, Brockton, Mass., assignor to Field and Flint Co., Brockton, Mass., a corporation of Massachusetts

Application July 5, 1934, Serial No. 733,836

5 Claims. (Cl. 36—17)

My invention, which relates to shoes, and has among its objects the provision of an improved waterproof construction, will be best understood from the following description when read in the light of the accompanying drawing of an example of shoe constructed according to the invention.

In the drawing:

Fig. 1 is an elevation of a shoe according to 10 the invention; and

Fig. 2 is a section on line 2—2 of Fig. 1.

Referring to the drawing, which illustrates one form of the shoe according to the invention, I have shown a common construction of welt shoe 15 having the insole 1, welt 3, and uppers, which latter in the present embodiment of the invention comprise the outer leather layer 5 and an inner lining 7 of textile material or soft leather or combinations of the two.

20 As shown, the insole is provided with a channel 9 and the welt with a groove 11, a line of stitching, the stitches 13 of which extend from the channel 9 of the insole to the groove 11 of the welt, being provided for securing the welt 25 and upper parts in assembled relation with the insole. The sole 15, as shown, is secured to the welt 3 in the usual manner by a line of stitching having the stitches 17.

The above described construction of shoe provides a space between the insole and welt filled by the leather and lining of the uppers. The seam or crack thus existing forms a means whereby water can leak into the interior of the shoe. Also, in such a shoe, water can leak into 35 the interior thereof by way of the welt groove and channel of the insole through the line of stitching. Further, the textile lining, when employed, has its edges exposed at the outer surface of the insole and forms a means which tends to 40 act as a wick to draw moisture into the interior of the shoe. Still further, the material of the insole commonly is of a rather spongy grade of leather with the split surface thereof exposed at the outer side, and this surface readily absorbs moisture. Also, the upper leathers being 45 thin, moisture tends to penetrate them and moisten the lining and from this source wet the sock or stocking of the wearer of the shoe.

For waterproofing the shoe, in the present embodiment of the invention the upper leather has applied thereto at the inner side thereof what amounts to a thin sheet 19 of flaccid, wear-resisting, waterproof material, preferably such as will provide a smooth surface. The layer of 55 the material 19, as shown, extends into the seam

between the welt and insole, and preferably is of such height as to terminate at approximately the center of the height of the shoe at the toe portion, as in indicated at 21 in Fig. 1. At its rearward end the layer preferably terminates 5 at the heel portion of the shoe in overlapping relation to the counter 23. If desired, however, the coating 19 may be of a different extent, as, for example, it may be co-extensive with the entire extent of the upper leather or may be 10 confined to any desired portion thereof.

The coating 19, shown of exaggerated thickness in the drawing, is applied to the upper leather as a liquid and dried before the lining is assembled with the upper leather and the uppers 15 drawn over the last and secured to the insole and welt. If desired, a smooth layer 25, also shown of exaggerated thickness in the drawing, of like waterproof material may be applied to the "top" surfaces of the insole and welt and permitted to dry after the shoe is lasted and before the filler 21 and sole are applied. Preferably, sufficient material is applied in forming the layer 25 to fill or close the channel 9 and groove 11. If desired, the layer 25 may extend over the 25 entire width of the "top" surfaces of the welt and insole, or it may be of such width as merely to fill or close the channel 9 and groove 11 and cover the exposed surface portions of the welt and insole between the groove and channel. 30 The material of the coating is preferably so compounded as to have the property of being able to impregnate the exposed portions of the textile lining 7 and stitches 13 adjacent the "top" surfaces of the insole and welt. In this way the 35 seam between the insole and welt may be completely waterproofed, and, as the material of which the coating is formed contains a volatile solvent, the layer 25, in cases where it contacts the layers 19, is integrally united therewith. 40

I have found as suitable for use in forming the above described waterproof sheets or coatings a nitrocellulose base containing a plasticizer such as di-ethyl-phthalate or castor oil dissolved in a volatile solvent, the latter preferably being a mixture of ethyl alcohol and amyl acetate. The nitrocellulose base is preferably celluloid, although nitrated cotton, or wood fibers, or other nitrocellulose material may be employed. The 50 di-ethyl-phthalate or other plasticizer makes the celluloid flaccid. The amyl acetate causes the celluloid or other nitrocellulose base to be absorbed by the insole and upper leather so as to penetrate them to a slight extent and secure 55

good adherence. When mixed with ethyl alcohol, amyl acetate makes a stronger solvent than either ethyl alcohol or amyl acetate used alone.

As suitable proportions of constituents of the 5 coating material, but without limitation thereto, it has been found that satisfactory results will be secured by using one pound of celluloid to each gallon of a mixture of the other constituents in approximately the following volumetric 10 proportions: ethyl alcohol, 75%; amyl acetate, 20%; di-ethyl-phthalate, 5%.

The above proportions are capable of considerable 15 variations. Preferably the di-ethyl-phthalate is varied to control the flaccidity of the celluloid or other nitrocellulose employed, and other celluloid solvents may be employed as substitutes for the ethyl alcohol and amyl acetate, the latter two substances, however, preferably 20 being employed for the reasons above pointed out.

It has been found that the above described compound, when applied to the shoe, has wearing 25 qualities commensurate with the wearing qualities of celluloid and at the same time is flaccid, which secure a degree of durability which would 30 not be secured were the ordinary celluloid solution applied to the shoe. The tough, horn-like character of the coating is such that it resists wear when subjected to friction, and no cracks or checks occur when the shoe is in use as the 35 flaccidity of the material is such that the leather may be bent or crumpled without fracturing the coating.

It will be understood that although a welt 35 form of shoe is illustrated, the same constitutes but one example of the invention, and that the coating is equally applicable to the seams, insoles and uppers of other forms of shoes.

I claim:

1. A shoe having an insole, welt, uppers and sole, said uppers at their lower edge portions being positioned between said welt and insole and the uppers and welt being secured to the insole by a line of stitching, the stitches of which extend from the under side of the welt to the under side of the insole, a layer of non-tacky, flaccid, waterproof material in adhering relation to the under side of said insole and welt but in 45 non-adhering relation to said sole, said layer closing the joint between said welt, uppers and insole and the exposed sides of said line of stitching on the welt and insole, and a layer of similar material on an inner surface portion of said uppers above said insole and covering the 50

adjacent portion of said uppers which is between said insole and welt.

2. A shoe having an insole, welt, uppers and sole, said uppers at their lower edge portions being positioned between said welt and insole and the uppers and welt being secured to the insole by a line of stitching, the stitches of which extend from the under side of the welt to the under side of the insole, a layer of non-tacky, flaccid, waterproof material in adhering 10 relation to the under side of said insole and welt but in non-adhering relation to said sole, said layer closing the joint between said welt, uppers and insole and the exposed sides of said line of stitching on the welt and insole, and a 15 layer of similar material on an inner surface portion of said uppers above said insole and covering the adjacent portion of said uppers which is between said insole and welt, the last mentioned layer being integral with the first 20 mentioned layer.

3. A shoe having an insole, welt, uppers and a sole, said uppers at their lower edge portions being positioned between said welt and insole, and a non-tacky, flaccid, wear-resisting, adhering 25 coating of waterproof material on an inner surface portion of said uppers above said insole extending to the adjacent portion thereof that is between said welt and insole.

4. A shoe having an insole, welt, uppers comprising an outer layer and a lining, and a sole, said uppers at their lower edge portions being positioned between said welt and insole, and a non-tacky, flaccid, wear-resisting adhering coating of waterproof material on an inner surface 30 portion of said outer layer of said uppers above said insole in non-adhering relation to said lining, said coating extending to the adjacent portion of said uppers that is between said insole and welt.

5. A shoe having an insole, welt, uppers and sole, said uppers at their lower edge portions being positioned between said welt and insole and the uppers and welt being secured to the insole by a line of stitching, the stitches of which 45 extend from the under side of the welt to the under side of the insole, non-tacky, flaccid, waterproof material in non-adhering relation to said sole closing the joint between said welt, uppers and insole, and a layer of similar material on an inner surface portion of said uppers above said insole and covering the adjacent portion of said uppers which is between said insole and welt.
